United States Patent Office

Des. 212,903
Patented Dec. 10, 1968

212,903

VEHICLE CLEANING ARCH

Earl Dallas Smith, 6202 E. Sage Drive,
Scottsdale, Ariz. 85251

Filed Dec. 18, 1967, Ser. No. 9,831

Term of patent 14 years

(Cl. D49—12)

Fig. 1

Fig. 2

Fig. 3

Fig. 4

FIG. 1 is a front elevational view of a vehicle cleaning arch showing my new design.

FIG. 2 is a rear elevational view thereof.

FIG. 3 is a top plan view thereof.

FIG. 4 is a left-hand side elevational view thereof.

The right-hand side is a mirror image of the left-hand side.

I claim:

The ornamental design for a vehicle cleaning arch, substantially as shown and described.
